United States Patent Office

Des. 224,146

Patented July 4, 1972

224,146

HEIGHT GAUGE

Nicholas M. Milan, 21664 Newcastle,
Harper Woods, Mich. 48236

Filed Mar. 18, 1971, Ser. No. 125,924

Term of patent 14 years

Int. Cl. D10—04

U.S. Cl. D52—6

FIG. 1 is a side elevational view of a height gauge showing my new design;

FIG. 2 is a front elevational view thereof; and

FIG. 3 is a top plan view thereof.

I claim:

The ornamental design for a height gauge, substantially as shown.
